Patented July 10, 1917.

UNITED STATES PATENT OFFICE.

JOHN W. HIER, OF HUNTINGTON, INDIANA; CHARLES A. BUTLER ADMINISTRATOR OF
SAID JOHN W. HIER, DECEASED.

GARBAGE AND REFUSE INCINERATOR.

1,233,288.

Specification of Letters Patent. Patented July 10, 1917.

Application filed April 2, 1915. Serial No. 18,690.

To all whom it may concern:

Be it known that I, JOHN W. HIER, a citizen of the United States, residing at Huntington, in the county of Huntington and State of Indiana, have invented new and useful Improvements in Garbage and Refuse Incinerators, of which the following is a specification.

This invention relates to garbage and refuse incinerators of the type wherein garbage or refuse is fed into the incinerator from the top and drawn off through a suitable withdrawal opening on the side.

The principal object of the invention is to improve and simplify the general construction of devices of this character.

A second object of the invention is to provide an improved construction of incinerator wherein the course or path of the hot gases used to dry out and incinerate the garbage or refuse will be so regulated as to provide increased economy in fuel consumption and increased efficiency in operation.

A third object of the invention is the provision of improved means in the incinerator for the economical production of a supply of steam adapted to be utilized for the treatment of the garbage or refuse at certain times in the incinerating operation.

A fourth object of the invention is the provision of an improved arrangement of air space surrounding the incinerating chamber and having communication therewith and means for controlling the admission of free air thereto.

With the above and other objects in view, the invention consists in general of certain novel details of construction and combination of parts hereinafter fully described, illustrated in the accompanying drawings and specifically claimed.

In the accompanying drawings, like characters of reference indicate like parts in the several views, and:

Figure 1 is a section on the line 1—1 of Fig. 2;

Fig. 2 is a view partly in front elevation and partly in section on the line 2—2 of Fig. 1;

Fig. 3 is a section on the line 3—3 of Fig. 1; and

Fig. 4 is a section on the line 4—4 of Fig. 1;

In carrying out the objects of the invention I preferably group two furnaces, A, B together in a common setting 10, one being

a right-hand furnace and the other a left hand furnace. Each of these furnaces consists of a substantially dome-shaped outer shell 11 having the general form of an elongated hemisphere and between this outer shell and the setting is a packing of rammed cinders or the like.

Spaced within the outer shell 11 is an inner shell 13 concentric to the outer shell so that an air space 14 which communicates with an inlet opening 15 controlled by a damper 16 is provided. This air space 14 furthermore communicates with the interior of the furnace through an opening 17 at the top of the roof, this opening being aligned with a similar opening 18 through the outer shell 11 and dumping floor 19. Normally, the opening 18 is closed by a plug valve 20.

One side of the furnace is flattened, as at 21, and adjacent this side is a fire grate 22 extending over an ash pit 23, suitable communication being afforded through the setting 10 by the fuel feed and ash pit door openings 24 and 25.

Disposed centrally of the width of the furnace is a passage 26, the ends of which are separated by a bridge wall 27. The inner end of this passage is covered by a grating 28 disposed directly below the openings 17 and 18 while a draw-off grate 29 covers the outer end of the passage. Over this draw-off grate is an arch 30 opening outward through a door opening 31, the end 26 opening outward through a door opening 32. Between the grates 22 and 29 is an up-standing baffle 33 so that the flames and gases of combustion will follow the path of the arrows, *c*, the air currents being indicated by the arrows *d*.

Situated between the two furnaces is a stack 34 which communicates with the furnaces by flues 35 controlled by dampers 36. By-passes 37 lead from the flues 35 to an up-take 38 which communicates with a tubular boiler 39 having valve controlled inlet and outlet pipes 40, the boiler being mounted in a suitable enlargement of the up-take which has communication with the stack through a passage 41 controlled by a damper 42. By this means the boiler may be used, when desired, to generate steam for the purposes of using the same to increase the drafts, operating a drying fan or any other desired purpose, the connections for these different purposes not being deemed

necessary to be shown as such connections form no part of the present invention.

In order to insure both proper drainage and the proper flow of the products of combustion, the floor of the furnace is made in the form of a helix, the axis of which is the center line, so that all the drainage from the mass of refuse to be incinerated will flow toward the center, while, at the same time, the axis of the cone formed by dumping material down the opening 18 will be slightly tilted to one side to cause distribution of the flame and gases of combustion. To aid in this drainage I further provide curved passages 43 extending from the floor of the furnace to the passage 26 and located above the inner end of the grate 29 so that the drainage may be attained around the grate.

In the operation, a fire is built on the grate 22 and after being well started refuse is dumped through the opening 18. By properly regulating the damper 16 the air may be admitted above the pile of refuse and material dried out, what may be termed the free liquid drawing off through the grate 28 or passing down through the openings 43. By manipulating the dampers, the hot gases may be sent either through the stack direct or through the boiler.

30 There has thus been provided a simple and efficient device of the kind, described and for the purpose specified.

Having thus described my invention, I claim:—

35 1. A refuse incinerator, inner and outer furnace shells separated to provide an air space between said shells, an incinerating chamber of substantially elongated dome-

shape having a fire grate adjacent one end and a withdrawal grate intermediate the ends, a baffle extending upward from floor to roof of the chamber between the grates, and valve-controlled means to admit air centrally at the top of the furnace and also to the air space between the shell.

40 2. A refuse incinerator including a chamber having an inner and outer shell separated to provide an air passage having communication with the interior of the chamber at the top thereof, valve-controlled means 50 for admitting air to the air space and to the interior of the inner shell, the chamber further having a helical floor with its lowest point located perpendicularly beneath the communication between the air passage and 55 the chamber, the floor of the chamber having an opening at its lowermost point, a grating covering said opening, the incinerator having a passage leading from the opening to the exterior.

60 3. A garbage incinerator, comprising dome-shaped shells forming an incinerating chamber, the shells being spaced from each other to form an air-heating chamber, a firebox in communication with the incinerating 65 chamber, the shells having aligned feed openings at the top thereof, and said air chamber being in communication with the outer atmosphere and with said feed openings.

65 In testimony whereof I have hereunto set my hand in presence of two subscribing witnesses.

JOHN W. HIER.
